UNITED STATES PATENT OFFICE.

GEORGE O. BLANCHARD, OF NAPOLEONVILLE, LOUISIANA.

HEAD COVER FOR INTERNAL-COMBUSTION ENGINES.

Application filed January 19, 1921, Serial No. 438,464. Renewed July 22, 1922. Serial No. 576,872.

To all whom it may concern:

Be it known that I, GEORGE O. BLANCHARD, a citizen of the United States, residing at Napoleonville, in the parish of Assumption and State of Louisiana, have invented certain new and useful Improvements in Head Covers for Internal-Combustion Engines, of which the following is a specification, reference being had to the accompanying drawings.

This invention relates to head covers for internal combustion engines, and more particularly to a cover for internal combustion engines involving valve gearing of the type commonly designated as overhead.

An important object of the invention is to provide means for protecting the rocker shaft and arms and the ends of the valve stems and their valves and bearings from the collection of dust and dirt.

A further object of the invention is to provide means for lubricating the valve gearing in order to eliminate the tapping noises commonly present in their operation.

A further object of the invention is to provide means for collecting the oil from the oily vapors arising from the base of the internal combustion engine and subsequently applying the same to the valve gearing to lubricate the valve gearing.

Other objects and advantages of the invention will become apparent throughout the course of the following description:

In the accompanying drawings, wherein for the purpose of illustration is shown a preferred embodiment of my invention, and wherein like reference characters designate like parts throughout:

Figure 1 is a side elevation of an internal combustion engine having my invention applied thereto;

Figure 2 is a plan view thereof;

Figure 3 is a rear elevation thereof;

Figure 4 is a section taken on the line 4-4 of Figure 2;

Figure 5 is a section taken on the line 5-5 of Figure 2;

Figure 6 is a section on the line 6-6 of Figure 2, and

Figure 7 is a section on the line 7-7 of Figure 2.

Referring now more particularly to the drawings, the numeral 10 indicates the cylinder of an internal combustion engine and the numeral 11 the base thereof having the usual breather pipe 12, by means of which

oil is supplied to the base and back pressure, caused by the leakage of the exploded gas in the cylinders past the pistons to the base, is allowed to escape.

The numeral 13 designates the usual cylinder head employed in valves having overhead gearing and the numeral 14 designates the valve which normally is held against the seat by means of the spring 14^a. Extending upwardly from the head 13 are standards 15 in which is mounted a shaft 16 having mounted for oscillation thereon rocker arms 17, one end of which contacts the stem of the valve 14 and the other end of which engages a lift rod 18 which is actuated in the usual manner by the cam 19. The cam 19 serves to cause the rocker arm to oscillate about its pivot and open the valve 14 against the action of the spring 14^a, the lift rod being maintained against the cam by the action of the spring and the spring returning the rocker arm 17 to the dotted line position upon each release by the cam 19.

C designates a casing adapted to fit upon the upper surface of the head 13 to form a cover for the valve gearing to protect the same against dust and dirt. With the forward end of this casing C a flexible conduit 20 communicates, having at its free end a slip joint connection 21 adapted to coact with the opening of the breather pipe 12 so that the conduit 20 may conduct the oil vapors from the base 11 to the casing C. The casing C is provided at its opposite end portion with a plurality of openings 22 permitting the escape of the vapors.

Secured to the under surface of the top 23 of the casing C, as by means of rivets 24, or the like, is a compressible absorbent pad 25 formed of felt or some similar material. The rivets 24 or similar attaching members which may be employed are preferably of the removable nature in order that the felt pad 24 may be replaced when it becomes worn in use. The conformation of the body portion 23 of the casing C is such that the rocker arms 17 engage with their ends the absorbent pad 25, for a purpose presently to appear. The pad 25 is preferably thickened or sags above the shaft 16 so that it contacts the shaft as at 25^a.

The casing C may be secured to the head in any desired manner. In the present instance, I have illustrated this attaching means as comprising a stud bolt 19^a engaging in the head 13 of the cylinder. Means

are preferably provided for furnishing oil to the felt pad 25 as for example by an oil cup 26 extending through the metal of the top 23 and delivering its contents upon the 5 felt pad.

In the operation of an engine equipped with my device, the oil vapors from the engine base are conducted through a conduit 20 to the casing C and are constantly passing therethrough so that the head and valve 10 gearing are thoroughly ventilated. These vapors coming into contact with the felt pad 25 deposit a portion of their oily contents thereon and pass out of the casing through 15 the openings 22. The rocker arms 17 in their operation contact the felt pad 25 and, accordingly, receive therefrom a portion of the deposited oil, in turn transmitting this oil to the lift rods 18 and to the stem of the 20 valve 14. The shaft 16 by its contact with the felt pad 25 at 25^a likewise receives the lubricant therefrom. In event of the oil supply from the vapors arising from the base is not sufficient to the needs of the 25 rocker arms and their associated mechanism, additional oil may be supplied through the cups 26 and will be held in suspension by the felt pad until released by the compression of the felt pad 25 by the ends of the 30 rocker arms 17.

From the foregoing it will be obvious that I have constructed a cover for the heads of internal combustion engines provided with overhead valve gearing which is particularly 35 well adapted for use by reason of the fact that it effectively prevents the collection of dust and dirt upon the valve gearing and by reason of the fact that it provides sufficient lubrication for the valve gearing. It will 40 likewise be obvious that the construction hereinbefore set forth is merely one specific embodiment of my invention which I have found particularly advantageous in use, and it will be understood that various structural 45 changes will necessarily be resorted to in applying my invention to internal combustion engines of various types. I, accordingly, do not limit myself to the specific structure hereinbefore set forth, except as so limited 50 by the subjoined claims.

What I claim is:

1. In combination with an internal combustion engine embodying overhead valves and operating mechanism therefor embodying rocker arms mounted upon the head of the engine, a casing secured to the engine 55

head and enclosing the valve gearing carried thereby, a conduit connecting said casing with the interior of the engine base and means within the casing for collecting oil from the vapors from the base and depositing the same upon said rocker arms. 60

2. In combination with an internal combustion engine embodying a head and valve operating mechanism carried by said head and embodying oscillatory rocker arms, a casing secured to said head and enclosing said valve operating mechanism, an absorbent pad carried by said casing and against which the ends of said rocker arms engage 65 and means for delivering lubricant to said absorbent pad, comprising a conduit connecting said casing with the interior of the engine base. 70

3. In combination with an internal combustion engine embodying overhead valves, an operating mechanism therefor embodying rocker arms mounted upon the head of the engine, a casing secured to the head of the engine enclosing the valve operating 75 mechanism carried thereby, a conduit connecting said casing with the interior of the engine base, means within the casing for collecting oil from the vapors from the base and depositing the same upon said rocker arms embodying an absorbent member disposed within said casing and against which said rocker arms engage and additional means for delivering oil to said absorbent member. 80

4. In combination with an internal combustion engine embodying overhead valves, an operating mechanism therefor embodying a rock shaft mounted upon the head of the engine, rocker arms carried by the rock shaft, a casing secured to the head of the engine and enclosing the valve operating mechanism carried thereby, a conduit connecting said casing with the interior of the engine base for conducting vapors from the 95 base of the engine to said casing, means within the casing for collecting oil from the vapors from the base and depositing the same upon said shaft and rocker arms embodying an absorbent member disposed within the casing and embodying portions against which said shaft and rocker arms engage. 100

In testimony whereof I hereunto affix my signature.

GEO. O. BLANCHARD.
